UNITED STATES PATENT OFFICE.

CHARLES STOLBERG, OF TOLEDO, OHIO, ASSIGNOR TO AMERICAN CAN COMPANY, OF JERSEY CITY, NEW JERSEY, A CORPORATION OF NEW JERSEY.

SHEET-METAL CARTON-CABINET.

SPECIFICATION forming part of Letters Patent No. 723,941, dated March 31, 1903.

Application filed September 4, 1902. Serial No. 122,046. (No model.)

To all whom it may concern:

Be it known that I, CHARLES STOLBERG, a citizen of the United States, residing in Toledo, in the county of Lucas and State of Ohio, have invented a new and useful Improvement 5 in Sheet-Metal Carton-Cabinets, of which the following is a specification.

My invention relates to improvements in sheet-metal cabinets for holding and delivering cartons, boxes, cans, or packages.

The object of my invention is to produce a cabinet of a simple, efficient, and durable construction, of a neat appearance and capable of being finely decorated, which will be attractive and ornamental, and which will serve 15 for conveniently holding, handling, or delivering cartons, boxes, cans, or packages.

My invention consists in the novel construction of parts and devices and in the novel 20 combinations of parts and devices herein shown or described and by which this object or result is accomplished.

In the accompanying drawings, forming a part of this specification, Figure 1 is a side 25 elevation of a sheet-metal carton-cabinet embodying my invention. Fig. 2 is a vertical cross-section on line 2 2 of Fig. 1, and Fig. 3 is a partial horizontal section on line 3 3 of Fig. 1.

30 In said drawings, A represents the base of the cabinet, the same being preferably of wood; and B is the bottom plate, the same being of sheet metal and having a curved or flaring portion b and a downwardly-projecting 35 flange b', embracing and covering the edges of the wood base A.

D is the vertical longitudinal center plate of the cabinet, which separates the two series 40 of upright compartments CC' from each other and which is provided at its ends with right-angle flanges d, uniting it to the sheet-metal vertical end plates D' D' of the cabinet, the same being preferably soldered thereto. The longitudinal center plate D also has a flange 45 d' at its lower edge for firmly securing it, preferably by solder, to the sheet-metal bottom B. The vertical end plates D' D' of the cabinet are each provided at each edge with rolls d', forming upright columns, preferably about a 50 half-inch in diameter, at the four corners of

the cabinet, which serve to give strength and rigidity to the cabinet as a whole and to the sheet-metal end plates and also a neat and ornamental appearance.

F F are the cross-partitions between the two 55 sets of upright compartments C C and C' C' of the cabinet, the same being of sheet metal and provided at their inner edges with right-angle flanges f for securing the same to the longitudinal center plate D, the same being 60 preferably so secured by soldering. The center plates F are each furnished or preferably furnished with a notch F' at its lower outer corner, and the end plates D' are also furnished or preferably furnished with corresponding notches D' at their outer lower corners. Each of the cross-partitions F has at 65 its outer upright edge a pair of columns or rolls g g', preferably of cylindrical form, one of said columns or rolls being preferably 70 formed integrally with the cross partition-plate F and the other, g', being formed of a column plate or strip G, which is securely fixed, preferably soldered, to the cross-partition F. The rolls or columns g g' are preferably 75 cylindrical or substantially cylindrical in form, and, in connection with the corresponding rolls or columns d' on the end plates D', form vertical guides for holding the cartons, boxes, cans, or packages in the 80 compartments C C', while at the same time exposing them to view. The guide-columns g' and d' extend down to the notches F' and D' respectively, and said notches F' and D' slightly exceed in vertical dimension 85 the thickness of the cartons or packages X, which are placed in the cabinet, so that the column-guides will prevent lateral or outward movement of all the cartons in the compartments of the cabinet excepting the lowermost 90 carton in each compartment, while at the same time permitting the lowermost carton in each compartment to be readily ejected.

H is the top of the cabinet, the same being 95 preferably of sheet metal and surrounding and embracing the end plates D' and the roll or column plates G, to all of which the top piece is preferably secured by solder. The top piece H has a roll h at its lower edge to strengthen and stiffen the same and give an 100

ornamental finish and appearance to itself and to the cabinet as a whole, and an outwardly-flaring part h' , which terminates in an upright flange h^2 , having a downward fold 5 h^3 at its upper edge, all of which also serves to stiffen and strengthen the top piece and give rigidity and firmness to the cabinet as a whole, while also producing a neat and ornamental appearance. The top piece H is 10 also provided at the lower edge of the upright flange h^2 with shelves or shoulders h^4 , preferably formed of bent pieces of sheet metal and soldered to the top piece, to receive and support the lid K of the cabinet, the shelves or 15 shoulders being preferably located at the corners of the top piece and also, if desired, along its longitudinal sides. The lid K rests on the shoulders h^4 within the flange h^2 of the top piece and is provided with downturned 20 flanges K' at its marginal edges, which serve to stiffen the same, and also with an upright longitudinal plate K², which serves as a handle for lifting the lid and also to give an ornamental finish to the cabinet and serve as 25 a sign-plate for the name of the party producing or dealing in the goods contained in the cabinet.

As my improved cabinet is or may be made as to all its exterior portions and longitudinal 30 and cross partitions of sheet metal, and preferably of tin-plate, it is adapted to receive a fine decoration, like other decorative tinware, and is at the same time very durable and easily kept in repair and in a perfectly clean 35 and neat appearance.

As my cabinet contains two sets or series of vertical compartments arranged back to back, the cabinet having a double front or two fronts, the same may be made very compact and substantial, while at the same time 40 containing a large number of compartments.

The top piece H at its upright portion h^5 affords means for placing thereon over each compartment the name of the article contained in the cartons, boxes, cans, or packages placed in each compartment—as, for example, “Pepper,” “Cinnamon,” “Cloves,” “Allspice,” “Ginger,” “Mustard,” &c.

Each of the vertical or upright compartments C C' is provided at the inner face or wall thereof with a thin flat flexible sheet-metal carton-ejector spring or strip M, soldered or otherwise secured at its upper end to the center plate D and projecting at its 55 lower end through a slot b^2 in the bottom plate B and connected at its lower end with a pull-rod N, having a knob or handle n at its outer end and extending through a hole b^3 in the flaring or curved portion b of the 60 bottom plate B, so that by pulling on the pull-rod the lower portion of the flexible or spring ejector-strip M will act upon the lowermost carton X and slide the same out from under the pile or stack of cartons in the vertical 65 compartment sufficiently to enable it to be grasped by the fingers and pulled out. The pull-rods N are preferably connected to the

flat ejector strips or springs M by an eye or hook n', formed on the inner end of the pull-rod. As the ejector strips or springs M are 70 thin and flat and flexible and secured at their upper ends only to the center plate D, they do not offer any obstruction to the downward feed of the cartons or packages X in the compartments C or C', while at the same time 75 they operate efficiently to push out the lowermost cartons, while the guides or columns g, g', or d³ hold all the cartons in place in the compartment, excepting the lowermost one. This thus affords a very simple, neat, and 80 cheaply-constructed means for properly and efficiently withdrawing the lowermost carton from each compartment.

I claim—

1. A sheet-metal cabinet having a series of 85 upright compartments, each having an open front or face furnished with columns or guides for preventing lateral or outward movement of the cartons or packages therein excepting the lowermost one, said columns or guides 90 being notched or cut away at the bottom for the thickness of a carton or package and each compartment having a thin, flat, flexible ejector-strip secured at its upper end to the back wall of the compartment, and a pull-rod attached to the lower end of said strip, whereby the lowermost carton or package can be slipped out sufficiently to enable its front end to be grasped by the fingers, substantially as 95 specified. 100

2. A carton-cabinet having an upright compartment provided with a thin, flat, flexible carton-ejector strip attached at its upper end to the back wall of the compartment and furnished with a pull-rod at its lower end, substantially as specified. 105

3. A sheet-metal carton-cabinet having a bottom plate furnished with a series of transverse slots therein, a vertical longitudinal plate, a pair of vertical end plates, and a series of cross partition-plates forming a series of upright compartments, the end plates and cross partition-plates having at their outer edges columns or guides for preventing all the cartons except the lowermost ones in the 110 compartments being slipped out or moved horizontally, said columns or guides being notched or cut away at the bottom for the thickness of a carton or package, and thin, flat, flexible ejector strips or springs, one for 115 each compartment, and projecting at their lower ends through slots in the bottom plate, and pull-rods connected to the lower ends of the flexible ejector-strips, substantially as specified. 125

4. A sheet-metal carton-cabinet having a bottom plate furnished with a series of transverse slots therein, a vertical longitudinal center plate, a pair of vertical end plates, and a series of cross partition-plates forming in conjunction with said longitudinal center plate two sets or series of upright compartments, the end plates and partition-plates having at 130 their outer edges columns or guides for pre-

venting all the cartons except, the lowermost ones in the compartments, from being slipped out or moved horizontally, said columns or guides being notched or cut away at the bottom for the thickness of a carton or package, and ejector-springs, one for each compartment, secured at their upper ends to the longitudinal center plate and projecting at their lower ends through the slots in the bottom plate, and pull-rods connected to the lower ends of the ejector-springs, substantially as specified.

5. A sheet-metal carton-cabinet, comprising in combination a bottom plate, a vertical longitudinal plate, a pair of vertical end plates and a series of cross partition-plates dividing the cabinet into a series of upright compartments, each of the cross partition-plates having an integral hollow roll or column at its 15 front or outer upright edge, said hollow rolls or columns serving to stiffen and strengthen the cabinet and being notched or cut away at the bottom for the thickness of a carton or package to permit the removal of the lowermost 20 carton or package in each compartment while holding the others in place, substantially as specified.

6. A sheet-metal carton-cabinet, comprising in combination a bottom plate, a vertical longitudinal plate, a pair of vertical end plates, and a series of cross partition-plates dividing the cabinet into a series of upright compartments, each of the cross partition-plates having an integral hollow roll or column at its 15 front or outer upright edge, and the end plates having integral rolls or columns at their upright front or outer edges, said hollow rolls or columns serving to stiffen and strengthen the cabinet and being notched or cut away 25 at the bottom for the thickness of a carton or package to permit the removal of the lowermost carton or package in each compartment while holding the others in place, substantially as specified.

45. 7. A sheet-metal carton-cabinet, having a bottom plate, a vertical longitudinal plate, a pair of end plates, and a series of cross partition-plates dividing the cabinet into a series of upright compartments, each provided with an integral hollow column or guide at its front or outer edge and with an additional column or guide formed of a separate column-strip attached thereto, said hollow columns or guides serving to stiffen and strengthen the 50 cabinet and being notched or cut away at the bottom for the thickness of a carton or package to permit the removal of the lowermost carton or package while holding the others in place, substantially as specified.

60. 8. A sheet-metal cabinet, comprising in combination a bottom plate, a vertical longitudinal center plate, a pair of end plates, a series of cross partition-plates dividing the

cabinet into two sets or series of upright compartments in connection with the longitudinal plate, hollow columns or guides at the front or outer edges of the end plates and cross partition-plates, a top piece surrounding and embracing the end plates and partition-plates and the columns or guides thereon, said hollow columns or guides serving to stiffen and strengthen the cabinet and being notched or cut away at the bottom for the thickness of a carton or package to permit the removal of the lowermost carton or package while holding the others in place, substantially as specified. 65

9. A sheet-metal cabinet, comprising in combination a bottom plate, a vertical longitudinal center plate, a pair of end plates, a series of cross partition-plates dividing the cabinet into two sets or series of upright compartments in connection with the longitudinal plate, columns or guides at the front or outer edges of the end plates and cross partition-plates, a top piece surrounding and embracing the end plates and partition-plates and the columns or guides thereon, and a lid fitting on the top piece, substantially as specified. 70

10. A sheet-metal cabinet, comprising in combination a bottom plate, a vertical longitudinal center plate, a pair of end plates, a series of cross partition-plates dividing the cabinet into two sets or series of upright compartments in connection with the longitudinal plate, columns or guides at the front or outer edges of the end plates and cross partition-plates, a top piece surrounding and embracing the end plates and partition-plates and the columns or guides thereon, flexible ejector-springs secured at their upper ends to the longitudinal center plate, and furnished with pull-rods at their lower ends, substantially as specified. 95

11. A sheet-metal cabinet, comprising in combination a bottom plate, a vertical longitudinal center plate, a pair of end plates, a series of cross partition-plates dividing the cabinet into two sets or series of upright compartments in connection with the longitudinal plate, columns or guides at the front or outer edges of the end plates and cross partition-plates, a top piece surrounding and embracing the end plates and partition-plates 110 and the columns or guides thereon, flexible ejector-springs secured at their upper ends to the longitudinal center plate and furnished with pull-rods at their lower ends, said ejector-springs projecting at their lower end through 115 transverse slots in the bottom plate, substantially as specified. 120
